US00D794281S

(12) **United States Design Patent** (10) **Patent No.:** **US D794,281 S**
Crowe et al. (45) **Date of Patent:** **** Aug. 15, 2017**

(54) **GARMENT**(71) Applicant: **Milwaukee Electric Tool Corporation**,
Brookfield, WI (US)(72) Inventors: **Jason R. Crowe**, Seattle, WA (US);
Timothy Janda, Elkhorn, WI (US);
Kim Brannock, Bend, OR (US); **Jerry Gundersen**, Bainbridge Island, WA (US)(73) Assignee: **Milwaukee Electric Tool Corporation**,
Brookfield, WI (US)(**) Term: **15 Years**(21) Appl. No.: **29/542,031**(22) Filed: **Oct. 9, 2015**(51) LOC (10) Cl. .... **02-02**(52) U.S. Cl. .... **D2/829**(58) **Field of Classification Search**

CLAIM

We claim the ornamental design for a garment, as shown and described.

DESCRIPTION

FIG. 1 is a front perspective view of a garment, such as a vest.

FIG. 2 is a rear perspective view of the garment shown in FIG. 1.

FIG. 3 is a front view of the garment shown in FIG. 1.

FIG. 4 is a rear view of the garment shown in FIG. 1.

FIG. 5 is a right side view of the garment shown in FIG. 1.

FIG. 6 is a left side view of the garment shown in FIG. 1.

FIG. 7 is a front perspective view of a garment, such as a vest.

FIG. 8 is a rear perspective view of the garment shown in FIG. 7.

FIG. 9 is a front view of the garment shown in FIG. 7.

FIG. 10 is a rear view of the garment shown in FIG. 7.

FIG. 11 is a right side view of the garment shown in FIG. 7.

FIG. 12 is a left side view of the garment shown in FIG. 7.

FIG. 13 is a front perspective view of a garment, such as a vest.

FIG. 14 is a rear perspective view of the garment shown in FIG. 13.

FIG. 15 is a front view of the garment shown in FIG. 13.

FIG. 16 is a rear view of the garment shown in FIG. 13.

FIG. 17 is a right side view of the garment shown in FIG. 13; and,

FIG. 18 is a left side view of the garment shown in FIG. 13. The interior of the garment, which is shown in broken lines, forms no part of the claimed design. The broken lines having uneven lengths represent the boundary of the claimed design and form no part of the claimed design. The remaining broken lines in the figures represent stitching and are part of the claimed design.

In FIGS. 13-18, stippling and straight-line surface shading represent contrast in materials.
